UNITED STATES PATENT OFFICE.

GUSTAV HOLMES, JOHN M. BOSTROM, AND AXEL G. BOSTROM, OF MILWAUKEE,
WISCONSIN.

AUTOMOBILE-CURTAIN.

1,195,989.

Specification of Letters Patent. Patented Aug. 29, 1916.

Application filed August 9, 1915. Serial No. 44,407.

To all whom it may concern:

Be it known that we, GUSTAV HOLMES, JOHN M. BOSTROM, and AXEL G. BOSTROM, citizens of the United States, and residents 5 of Milwaukee, in the county of Milwaukee and State of Wisconsin, have invented new and useful Improvements in Automobile-Curtains, of which the following is a description, reference being had to the accompanying drawings, which are a part of this specification.

This invention has for its object to provide a curtain for automobiles which while possessing the desirable features of the folding side curtain is capable of being readily detached and is adapted for use with automobile tops as ordinarily constructed without necessitating special equipment for its installation.

With the above object in view the invention consists in a side curtain creased vertically so as to fold bellows-like with each inwardly folded crease slidably connected with a guide rod pivotally connected with 15 the edge of the curtain so as to swing from a horizontal position to a vertical position when the curtain is folded.

Another object of the invention is to provide narrow window lights in the several 20 sections of the curtain between the folds which window light may be readily inserted or removed and when in place will present a neat appearance and when broken may be quickly replaced without requiring stitching 25 or skilled labor.

With the above and other objects in view the invention consists in the curtain for automobiles and the like as herein claimed and all equivalents.

Referring to the accompanying drawings 30 of which like characters of reference indicate the same parts in different views: Figure 1 is a view taken from the inside of the automobile of a curtain constructed in accordance with this invention, the curtain being shown in its open or extended condition; Fig. 2 is a similar view thereof with the curtain in its folded condition; Fig. 3 is an enlarged view of one of the curtain 35 window lights with parts broken away and sectioned for clearness of illustration; Fig. 4 is a detail sectional view on the plane of line 4-4, Fig. 3, showing the locking clip in position for holding the slot of the window light frame closed; Fig. 5 is a similar

view showing the slot of the light frame open to receive the light; Fig. 6 is a sectional view on the plane of line 6-6, of Fig. 3; Fig. 7 is a plan view of the curtain in its folded condition; Fig. 8 is an edge 60 view of the curtain in its folded condition; Fig. 9 is a detail view similar to Fig. 3 showing a modified form of the light frame; Fig. 10 is an outside view of a portion thereof; Fig. 11 is a longitudinal vertical 65 sectional view thereof; Fig. 12 is an edge view of a portion of the frame before being secured to the fabric of the curtain; Fig. 13 is a sectional view thereof; and, Fig. 14 is an edge view thereof after being connected to the curtain.

In these drawings 15 indicates a fragment of an automobile body and 16 is the automobile top thereof mounted on bows 17 as usual. The bows and the body have 70 turn buttons 18 for engagement with eyelets 19 in the edges of the side curtain 20. The side curtain 20 is formed of a waterproof fabric which is regularly creased along vertical lines 21 so as to alternately 75 fold inwardly and then outwardly in the manner shown in Fig. 7 and each of the inwardly folding creases is provided near the upper edge of the curtain with metal loops 80 22 through which a guide rod 23 passes. 85 The guide rod 23 is pivotally connected at 24 to the rear edge of the side curtain 20 and at its front end is provided with a ball 25 or other suitable enlargement which will prevent its passing through the loops 22. 90 In opening the curtain from its folded position shown in Fig. 2 to its open or extended position shown in Fig. 1, the loops 22 slide on the guide rod 23 and when collapsing or folding the curtain said loops 95 traveling on the guide rod serve to guide the folding operation so that the operation may be quickly performed and the several creases of the curtain will fold in the proper direction to produce the neat compact arrangement shown in Fig. 2 where the curtain is folded close against the rear bow 17. The rear end of the guide rod 23 is slightly curved so that in this folded position of the curtain it will hang downwardly 100 as shown in Fig. 2 and retain the curtain in its folded condition.

Between each pair of creases 21 the curtain is preferably provided with a narrow vertical window light 26 which may be of 110

transparent celluloid or other suitable material and instead of permanently securing these window lights to the openings in the curtain by stitching them in place and by 5 stitching a binding around their edges as usual the present invention provides a sheet metal frame 27 formed of a strip of thin sheet metal bent reversely upon itself to form an S-shape in cross section, such strip 10 being also bent to form the oblong shape of the opening in the curtain with rounded corners. Because of the S-shape in cross section the frame 27 presents an inwardly opening groove to receive the edges of the window light 26 and an outwardly opening groove 15 to receive the edges of the fabric of the side curtain 20. Previous to inserting the frame in the opening of the side curtain the outer edge of the frame is left slightly open or 20 spread away from the intermediate portion thereof as shown by dotted lines in Fig. 6 to facilitate the admission of the edge of the opening of the curtain therein and spurs or projections 28 are formed in such intermediate portion extending toward such outwardly bent edge so that when the edge of the curtain opening is inserted in this groove and the outer edge of the frame is 25 pressed thereagainst as shown in the full lines of Fig. 6 these spurs or projections 28 pierce the fabric of the curtain to firmly secure the frame in place and prevent the edges of the curtain opening being pulled loose therefrom. These spurs or projections 30 35 may be formed in the thin sheet metal strip of the frame before the frame is bent up into shape and preferably extending throughout the length of the strip forming the frame.

40 At its upper end the frame 27 is provided with a slot 29 extending the full width of the frame and preferably formed in the intermediate portion thereof near the outer bend as best seen in Figs. 4 and 5 and when 45 this slot is sprung open as shown in Fig. 5 the sheet of celluloid or other material forming the window light may be passed through into or out of the inner groove of the frame. When the window light is in place the slot 50 is pressed to its closed position as shown in Fig. 4 and a sheet metal locking clip 30 which is clamped in place by one of the spurs or barbs 28 is bent down over the edge of the frame as shown in Fig. 4 to 55 hold the slot closed and thus prevent accidental displacement of the window light. An injured window light may be readily removed however by bending back the clip 30 and opening the slot as in Fig. 5.

60 In the modified form of the window light frame as shown in Figs. 9 to 14 inclusive, the strip of sheet metal 27' is bent to an S-shape in cross section so as to produce inwardly and outwardly opening grooves for 65 receiving the window light and the edge of the

curtain respectively as before, but the outwardly extending edge thereof is cut obliquely at intervals to form barbs or teeth 28' which are bent toward the intermediate portion of the strip as shown in Figs. 12 and 13 70 so that when the edge of the fabric is inserted in the outer groove and the metal strip is bent thereagainst these barbs will pierce the fabric and be clenched thereagainst as shown in Fig. 14. Furthermore this form 75 of the window light frame differs from the other in that notches 31 are provided in the inwardly projecting edge thereof at the sides near one end, which notches are of sufficient depth to make the opening 80 between them of approximately the width of the window light 26 and though the inwardly extending flange remains of full width at the extreme end of the frame to form a pocket 32 to receive the end of the 85 window light such width diminishes on leaving the end of the frame and merges with narrow inturned flanges 33 which extend to the notches 31. To insert the window light in the frame of this construction 90 one end of the window light is entered through the space between the notches 31 and is pushed into place in the inner groove of the frame, the flexible window light bending as it enters the notches 31, and then 95 when the lower end of the window light is fully seated in the inner groove of the frame the upper end of the window light is bent to permit its insertion in the pocket 32 and is sufficiently convexed to cause its edges to 100 clear the inturned flanges 33 until it lies flat against the intermediate portion of the frame where its resiliency will hold it in place until it is desired to remove it by the reversal of the operation for its insertion 105 just described.

The automobile curtain of this invention may be entirely detached from the bows in clear weather and may be quickly put in place when required and during threatening weather it may be folded against the bows in position to be quickly drawn to its open condition, the guide rod 23 facilitating the adjustments of the curtain and serving to hold it in its folded condition. The 110 window lights while firmly held in place by means of the metal frame may be readily replaced when broken or injured and instead of requiring a day's work of a skilled laborer in removing the fragments and binding and replacing new window lights as with the stitched method of attachment the replacement may be quickly performed by merely sliding the fragment of the old light 115 out of the frame and slipping a new window light in place. The time required in placing the window light frames in the curtain openings in the first place is much less than with the old method of stitching while the cost of 120 the metal frames produced in quantities is 125 130

approximately the same or somewhat less than the cost of the binding tape in the old form of construction. With the metal frames the flexible window lights are better 5 protected against breakage as they are sufficiently stiff to resist bending.

What we claim as our invention and desire to secure by Letters Patent is:

1. In a curtain window, the combination 10 of a curtain member provided with a window opening, a window light having the shape of the window opening but larger than the window opening so that its edges overlap the edges of the window opening and a 15 sheet metal frame bent to an S-shaped form in cross section to produce an outwardly opening groove receiving the edge of the window opening and to produce an inwardly opening groove receiving the edge of the 20 window light.

2. A curtain window light frame for automobiles and the like comprising a strip of sheet metal or the like material bent to produce an outwardly opening groove to receive 25 the edge of the window opening of the curtain and to produce an inwardly opening groove to receive the edge of the window light.

3. A windowed curtain for automobiles 30 and the like comprising a curtain member having a window opening, a window light frame of sheet metal or the like material bent reversely upon itself to produce an outwardly opening groove receiving the 35 edges of the window opening and to produce an inwardly opening groove receiving the edges of the window light, and barbs in the outwardly opening groove to engage the edges of the window opening.

4. A windowed curtain for automobiles and the like comprising a curtain member having a window opening, a window light, a frame of sheet metal or the like material bent reversely upon itself to form an 45 S-shaped cross section to provide an outwardly opening groove receiving the edges of the curtain member around the window opening, and to produce an inwardly opening groove receiving the edges of the window 50 light, spurs formed on the intermediate portion of the frame and projecting into the outwardly opening groove to engage the edges of the curtain, there being a slot in the inwardly opening grooved portion of 55 the frame through which the window light may pass, and a locking clip secured in the outwardly opening groove of the frame by

one of the spurs and adapted to be bent over the slotted portion of the frame for holding the slot closed.

5. A windowed curtain comprising a curtain member having a window opening, a window light of flexible material, a frame formed of a strip of sheet metal or the like material bent reversely upon itself to form 60 inwardly and outwardly opening grooves receiving the edges of the window light and the edges of the curtain member around the window opening respectively, and barbs formed in the outwardly turned edges of the frame to engage the curtain member, there being notches formed in the inturned edges of the frame through which the window light may pass on being inserted in or removed from the frame.

6. A windowed curtain for automobiles and the like comprising a curtain member, a flexible light, and an oval shaped sheet metal window frame formed of a strip of sheet metal bent reversely upon itself to 65 form an outwardly opening groove receiving the edge of the curtain member around the curtain opening and to form an inwardly opening groove receiving the edge of the window light, there being notches formed 70 in the inwardly extending edge of the frame at opposite points to permit of the passage of the window light therethrough, said inwardly extending edge of the frame forming a pocket at the end of the frame to receive 75 the end of the window light and forming a narrow flange extending from said pocket to the said notches.

7. A windowed curtain for automobiles and the like comprising a curtain member 80 having a window opening, a window light of flexible material, and a frame provided with an outwardly opening groove receiving the edges of the curtain member around the window opening and provided with an 85 inwardly opening groove receiving the edges of the window light, the wall of the inwardly opening groove being cut away on opposite sides of the frame to permit the flexible window light to pass therethrough 90 into the inwardly opening groove.

In testimony whereof, we affix our signatures, in presence of two witnesses.
